UNITED STATES PATENT OFFICE.

ALBERT A. GORDON AND ALFRED F. MORRELL, OF WORCESTER, MASSACHUSETTS,
ASSIGNORS TO CROMPTON & KNOWLES LOOM WORKS, OF WORCESTER, MASSA-
CHUSETTS, A CORPORATION OF MASSACHUSETTS.

REVOKING MECHANISM FOR AUTOMATIC LOOMS.

Application filed June 17, 1926. Serial No. 116,726.

This invention relates to an automatic loom of the pick and pick type, in which a plurality of shuttle boxes are provided at both ends of the lay. It sometimes happens 5 that a shuttle will fail to enter its shuttle box to the full extent, but will come to rest with one end portion projecting therefrom.

It is the general object of our invention to provide improved means for revoking the 10 transfer of a weft carrier to the shuttle when the shuttle fails to box, said means being also effective to disable the drop box mechanism and prevent shifting movement of the shuttle boxes under the same conditions and to 15 throw off the shipper to stop the loom.

Our invention further relates to arrangements and combinations of parts which will be hereinafter described and more particularly pointed out in the appended claims.

20 A preferred form of our invention is shown in the drawings in which

Fig. 1 is a front elevation of portions of a loom embodying our improvements;

Fig. 2 is a left hand side elevation of the 25 revoking mechanism and certain parts associated therewith;

Fig. 3 is a view similar to Fig. 2, but showing the parts in a different position;

Fig. 4 is a partial rear view, looking in 30 the direction of the arrow 4 in Fig. 2;

Fig. 5 is a detail plan view, taken along the line 5—5 in Fig. 1, and

Fig. 6 is a detail side elevation, looking in the direction of the arrow 6 in Fig. 1.

35 Referring to the drawings, we have shown portions of a loom including a loom frame 10, a lay 11 supported upon the usual swords 12, a plurality of shuttle boxes 13 rotatably mounted at the magazine end of the loom,

40 and a magazine indicated generally by the letter M. The rotary shuttle boxes are preferably actuated by a rack and pinion mechanism such as is disclosed in the prior application of Albert A. Gordon, Serial No.

45 16,791, filed March 19, 1925, and the racks are shifted vertically by a lifter rod 15 having a laterally projecting stud 16 engaged by a give-way device 17 forming the upper end of a link 18 which is pivoted on a crankpin

50 19 mounted on a rock shaft 20. The give-way device 17 comprises a portion 21 integral with the link 18 and a portion 22 (Fig.

6) pivoted at 23 to the portion 21, said parts being drawn together by a tension spring 24. When movement of the lifter rod 15 is prevented, as will be hereinafter described, the give-way device yields and slips idly upward past the stud 16, thus preventing damage to the mechanism.

Transfer mechanism.

Referring particularly to Figs. 2 and 3, we will now describe the transfer mechanism to which our improvements have been applied. The magazine M is provided with a transfer lever 25 having a hook 26 pivoted thereto and adapted to be swung rearward into the path of an actuator 27 having a cooperative hook at its upper end. The hook 26 is moved to operative position by the action 65 of the bell crank 30 having a lost motion connection through a link 31 to an arm 32 fixed to a shaft 33 which extends across the breast-beam 34 to the opposite side of the loom, where it is controlled by the weft detecting mechanism in the usual manner.

When substantial exhaustion of weft is indicated, the shaft 33 is rocked, swinging the bell crank 30 on its pivot and depressing the arm 35 of the bell crank against a spring 36 fixed on the front side of the hook 26. The hook 26 is thus moved yieldingly rearward into the path of the hooked upper end of the actuator 27, which is intermittently reciprocated vertically by suitable actuating 75 mechanism (not shown).

When the hook is engaged by the actuator, the transfer lever 25 is drawn downward and a change of weft in the active shuttle is effected. All of the parts thus far described are of the usual type and in themselves form no part of our present invention.

Revoking mechanism.

We will now describe more specifically 95 the mechanism which we have provided for revoking the transfer and prevent shifting of the shuttle boxes when a shuttle fails to box. For this purpose, a revoking arm 40 (Fig. 2) is pivoted at 41 on the transfer lever 25 and projects downward over the lay as the lay moves forward. The normal position of the revoking arm is as indicated in Fig. 2, the arm clearing the upper surface 100

of the lay 11 as the lay moves forward. If the shuttle fails to box completely, the projecting end of the shuttle will strike the arm 40, swinging it forward to the position indicated in Fig. 3.

A link 41^a is pivoted at 42 to the arm 40 and is provided with an L-shaped slot 43 which normally receives a stud 44 in its upwardly extending offset end portion 45, as indicated in Fig. 2. The stud 44 is fixed in the side of a lever 46 mounted upon a pivot 47 on the breast-beam 34 and having an upwardly projecting portion 48 adapted to engage a stud 49 projecting laterally from the hook 26.

When the revoking arm 40 is swung forward by engagement with a misplaced shuttle, the arm 48 of the lever 46 is pushed forward, moving the hook 26 to an inoperative position, as indicated in Fig. 3.

In order to prevent excess movement of the lever 46, the link 41^a is provided with a stud 50 adapted to engage a cam plate 51 secured to the breast-beam 34. When the lever 46 has been moved forward sufficiently to accomplish its functions, the stud 50 engages the fixed cam plate 51 and the link is raised thereby until the stud 44 passes into the longitudinal portion of the slot 43, which permits the link 41^a to slip idly past the stud during its continued forward movement.

Through the connections thus far described, the revoking arm 40 is effective to prevent actuating movement of the transfer lever 25 in the event of a misplaced shuttle.

We have also provided connections by which the revoking arm 40 is effective to prevent shifting movement of the shuttle boxes. For this purpose, the lever 46 is provided with a depending arm 55 (Fig. 2) having an end portion which normally holds a plunger 56 depressed against the tension of a spring 57. The plunger 56 is connected by a cord or chain 58 (Fig. 1) to a stud 59 (Fig. 5) fixed in the side of a pivoted locking member 60, having stop arms 61 and 62 projecting therefrom.

The lifter rod 15 is provided with a lug or offset projection 65 (Fig. 1) which normally clears the arms 61 and 62 as the lay moves forward, and the lifter rod is thus free to be shifted vertically. If, however, the arms 61 and 62 are swung from the full line position of Fig. 5 to the dotted line position in said figure, the arms will then be in the path of the lug or offset 65 when an attempt is made to move the lifter rod vertically. The stop arms will thus positively prevent movement of the lifter rod. The pivoted member 60 is mounted in fixed bearings 70, which may be supported by a suitable stand 71.

A spring 72 is connected to the pivot shaft 73 of the member 60 in such a way that

it tends to swing the arms 61 and 62 away from path of the projection 65. The spring 72, however, is of less strength than the spring 57 shown in Fig. 2, so that the spring 57 will readily overcome the spring 72 and swing the arms 61 and 62 to operative position when released by the forward movement of the revoking arm 40.

We have thus provided means for simultaneously disconnecting the transfer lever 25 from its actuating member 27 and for swinging the arms 61 and 62 to a position in which they prevent vertical movement of the lifter rod 15 and thus prevent shifting of the shuttle box until the shuttle is properly boxed.

Resetting mechanism.

We have also provided convenient means for resetting the magazine and the indicating mechanism after a transfer has been revoked. For this purpose the depending arm 55 of the lever 46 engages an upwardly extending arm 75 of a resetting lever 76 mounted upon a fixed pivot 77. The cam-like end of the lever 76 is engaged by a stud 78 on an arm 79 secured to a rock shaft 80 which extends across the loom and is connected to be rocked as the shipper is reset.

When the shaft 80 is thus rocked in the direction of the arrow α in Fig. 3, the stud 78 engages the cam face of the lever 76, turning the lever 76 in a clock-wise direction about its pivot 77 and swinging the lever 46 rearward to the initial position shown in Fig. 2. As this movement is taking place, the weight of the revoking arm 40 causes the arm 40 and link 41^a to also resume their original positions.

It is necessary, however, that the plunger 56 be depressed so as to clear the arm 55 of the lever 46 before return movement of the latter. For this purpose, I provide a stud 85 in the side of the plunger 56, which stud is engaged by a depressing lever 86, pivoted at 87 and engaged and depressed by the stud 78 as the shaft 80 is rocked about its axis. This downward movement of the lever 86 restores the plunger 56 to the depressed position indicated in Fig. 2, in which position it is held by the arm 55 of the lever 46 until the lever is again actuated to prevent transfer and shuttle change.

The resetting mechanism also has another function, namely, the stopping of the loom when actuated in the reverse direction. As the arm 76 is moved by a misplaced shuttle from the normal position shown in Fig. 2 to the position of Fig. 3, it engages the stud 78 and rocks the shaft 80 to throw off the shipper and stop the loom, thus affording additional protection in the event of a misplaced shuttle.

We have thus provided simple and effective mechanism by which the operation of

the transfer lever 25 and also the operation of the lifter rod 15 is effectively prevented in the event that the active shuttle fails to enter its shuttle box.

5 Having thus described our invention and the advantages thereof, we do not wish to be otherwise limited to the details herein disclosed but what we claim is:—

1. In a weft replenishing loom, a lay, a 10 magazine and a plurality of shifting shuttle boxes at one side of the loom, and means to revoke the transfer and prevent shifting of the shuttle boxes if the running shuttle engages said revoking means on forward 15 movement of the lay.

2. In a weft replenishing loom, a magazine and a plurality of shifting shuttle boxes at one side of the loom, and means directly engaged by a misplaced shuttle and effective to revoke the transfer and prevent subsequent shifting of the shuttle boxes.

3. In a weft replenishing loom, a lay, a magazine and a plurality of shifting shuttle boxes at one side of the loom, and a single revoking member positioned for engagement by a misplaced shuttle and connected to revoke the transfer and to prevent shifting of the shuttle boxes if the running shuttle engages said revoking member on forward movement of the lay.

4. In a weft replenishing loom, a lay, a magazine and a plurality of shifting shuttle boxes at one side of the loom, an actuating member for said boxes, a give-way device between said actuating member and said boxes, and means additional to the shuttle effective to hold said boxes from shifting movement with said actuating member if the running shuttle engages said revoking member on forward movement of the lay.

5. In a weft replenishing loom, a lay, a magazine and a plurality of shifting shuttle boxes at one side of the loom, an actuating member for said boxes, a give-way device between said actuating member and said boxes, a revoking member, and means to hold said boxes from shifting movement with said actuating member if the running shuttle engages said revoking member on forward movement of the lay, said holding means being controlled by said revoking member which is movable by direct engagement by the misplaced shuttle.

6. In a weft replenishing loom, a magazine and a plurality of shifting shuttle boxes at one side of the loom, a locking device for said shifting shuttle boxes, a spring normally acting to move said locking device to operative position, a stop normally preventing such movement, and shuttle-engaging revoking means effective to displace said stop.

7. In a weft replenishing loom, a magazine and a plurality of shifting shuttle boxes at one side of the loom, a transfer lever in said magazine, an actuator for said transfer

lever, a connection between said actuator and said lever movable to operative position upon indication of substantial weft exhaustion, a revoking member, and a connection from said member to said actuating connection, effective to displace said connection upon engagement of said revoking member by a misplaced shuttle.

8. In a weft replenishing loom, a magazine and a plurality of shifting shuttle boxes at one side of the loom, a transfer lever in said magazine, an actuator for said transfer lever, a connection between said actuator and said lever, means to move said connection to operative position upon indication of substantial weft exhaustion, and a revoking member by which said actuating connection is positively moved from operative position when said revoking member is engaged by a misplaced shuttle.

9. In a weft replenishing loom, a magazine and a plurality of shifting shuttle boxes at one side of the loom, transfer mechanism for said magazine, actuating means for said transfer mechanism, a revoking member, a connection from said member, effective to disable said actuating means upon forward movement of said revoking member by engagement with a misplaced shuttle, and means to disengage said connection from said actuating means during the continued forward movement of said revoking member.

10. In a weft replenishing loom, a magazine and a plurality of shifting shuttle boxes at one side of the loom, transfer mechanism for said magazine, actuating means for said transfer mechanism, a revoking member, a link connected with said member and having a stud and slot connection with said actuating means, and said link being effective to displace said actuating means upon forward movement of said revoking member by a misplaced shuttle.

11. In a weft replenishing loom, a magazine and a plurality of shifting shuttle boxes at one side of the loom transfer mechanism for said magazine, actuating means for said transfer mechanism, a revoking member, a link connecting said member with said actuating means and having an L-shaped slot therein with an operative and inoperative portion, said actuating means having a stud positioned in said slot and said link being effective to disable said actuating means upon forward movement of said revoking member by a misplaced shuttle, and means to move said link transversely and position said stud in the inoperative portion of said slot upon continued forward movement of said revoking member.

12. In a weft replenishing loom, a lay, a magazine and a plurality of shifting shuttle boxes at one side of the loom, and means to stop the loom and to revoke the transfer

and prevent shifting of the shuttle boxes if the running shuttle engages said revoking means on forward movement of the lay.

13. In a weft replenishing loom, a magazine and a plurality of shifting shuttle boxes at one side of the loom, and means directly engaged by a misplaced shuttle and effective to stop the loom and to revoke the transfer and prevent subsequent shifting of the shuttle boxes.

14. In a weft replenishing loom, a lay, a magazine and a plurality of shifting shut-

tle boxes at one side of the loom, and a single revoking member positioned for engagement by a misplaced shuttle and connected 15 to stop the loom and to revoke the transfer and to prevent shifting of the shuttle boxes if the running shuttle engages said revoking member on forward movement of the lay.

In testimony whereof we have hereunto 20 affixed our signatures.

ALBERT A. GORDON.
ALFRED F. MORRELL.
